UNITED STATES PATENT OFFICE

WILLIAM BROAD, OF BEAVER FALLS, PENNSYLVANIA, ASSIGNOR OF THREE-FOURTHS
TO HARRY E. McLAIN, OF PITTSBURGH, PENNSYLVANIA

INSULATING DEVICE

Application filed December 28, 1927. Serial No. 243,010.

My invention relates to insulating devices and particularly to supports for insulating crossed electrical conductors of different polarity in electrical wiring systems.

5 In electrical distributing systems employing "open work" wiring, it is frequently necessary to carry conductors of opposite polarity across one another. As the conductors are usually mounted on spaced insulating 10 brackets, or are supported by tubes extending through timbers, the conductors are free to flex. In pulling the conductor taut it frequently happens that the supporting devices yield or loosen sufficiently to permit the conductor to come into engagement with adjacent fixed conductors. In some cases the latter conductors are flexed from their original 15 positions. Where the conductors are covered with rubber or composition insulating 20 material and two conductors under tension are in direct engagement, the insulating covering is apt to be rubbed or scraped sufficiently to impair its insulating properties. In some cases the insulation is wholly torn 25 or worn away so that the current carrying wires of different polarity are brought into direct engagement. The engagement of the current carrying wires results either in a short circuit of sufficient magnitude to blow 30 out fuses or open-service switches for the distributing system, or, if of insufficient magnitude to interrupt service, it produces a condition of electrical arcing and sparking which is liable to ignite the adjacent timbers or 35 other inflammable material. Many fires have been started from such causes.

Heretofore electricians have taped a porcelain tube of the type common in "open work" wiring systems on one of the conductors at a point opposite the cross conductor. Upon lateral movement of one of the conductors relative to the other conductor, the crossing point is apt to shift to a point not opposite the tube. Where this condition is 40 observed the tube must be taped and shifted to the true cross point. However, it frequently happens that the electrical conductors are hidden from view and such relative movement is not observed. In such cases the 45 conductors are apt to lie in direct engagement

with each other with the resultant danger of a condition of short-circuiting.

To maintain crossed electrical conductors separated while permitting longitudinal movement of the individual conductors, I 55 provide an insulating device that is characterized by the use of one conductor for positively locking the insulating device in its assembled position. The separated conductors are free to move relative to each other and to 60 the insulating device.

The insulating device comprises a base member of substantially U-shape having a seat for a conductor at approximately the base thereof and aligned openings near the 65 ends of its arms. A second member having an opening is inserted between the arms of the base so that an electrical conductor extending through the openings in the arms and through the second member locks the insulating device in assembled position. The second member secures the conductor in the seat in the base member. Accordingly, the length of the leakage path between the two conductors is approximately half the width of the 70 second member plus its radial length from the opening. To provide for longitudinal movement of the conductor seated in the base relative to the insulating device, the second member may be made in the form of a roller. 75 Adjustment of the position of the insulating device is had by the longitudinal movement of one conductor through the openings in the base and in the second member and by the movement of the second conductor between 80 the base and the second member. The insulating device may be made of porcelain, hard rubber, phenolic condensation products, or 85 any other well-known insulating material.

The accompanying drawings illustrate the 90 present preferred embodiment of the invention, in which

Figure 1 is a perspective view of the insulating device in assembled position;

Figure 2 is a face view, partially in section, thereof; and

Figure 3 is a diagrammatic view of an electrical distributing system showing the application of my insulating device thereto.

Referring to Figures 1 and 2, I provide 95

insulating device 2 for separating crossed conductors of differing polarity. The insulating device comprises a base 4 of substantially U-shape having a seat 5 at substantially the bottom thereof for the reception of an electrical conductor and a second or closure member 6 mounted between the arms of the base 4. The base 4 is provided with openings 7 disposed near the ends of its arms in alignment with an opening 8 in the closure member 6. When fastening means 9, such as an electrical conductor, is passed through the openings 7 and 8, it serves to secure the closure member 6 and the base 2 in assembled relation. It is to be understood that the insulating device may be used as a support for electrical conductors by extending a wire, nail or the like through the openings 7 and 8. The base 2 and closure member 6 are of any non-magnetic material such as porcelain, hard rubber, phenolic condensation products and the like.

The insulating distance between a conductor 10 disposed in the seat 5 and the conductor 9 is approximately half the width of the closure member 6 and the distance from its lower edge to the opening 8. For maintaining this insulating distance substantially constant for different sizes of conductors 10, I provide the seat 5 with shoulders 11 that are closed by the outer edge of the closure member 6. With different sizes of wire the shoulders 11 and the edge of the closure member 6 cooperate to center it in the bottom of the seat 5. The edges 12 of the base 2 at the seat 5, are slightly rounded to prevent the tearing and cutting of the covering of the conductor 10, when the latter moves relative to the base.

To provide for relative longitudinal movement between the conductor 10 and the insulating device 2, the closure member 6 is made in the form of a roller, although it is to be understood that other shapes of the closure member 6 are contemplated within the scope of the invention. The conductor 9 is free to move through the openings 7 and 8 relative to the base 2. When the tension on the conductors 9 and 10 is such as to cause a relative movement of the insulating device 2 therebetween, the closure member 6 turns about the conductor 9 as the insulating device moves along the conductor 11. At the same time the conductor 9 slips through the openings 7 and 8 until a condition of equilibrium is arrived at.

Referring to Figure 3, one application of the insulating device is in use on "open work" systems of electrical distribution. In such systems conductors 14 and 15 of differing polarity are connected to branch circuits 16. The conductors are usually supported on porcelain knobs and tubes. It has heretofore been customary to place and tape a tube on the conductors of the circuits 16 extending

across the conductor 15. However, upon relative movement of the conductors, the tubes move out of alignment with the conductors which they are designed to normally protect. When such movement takes place, and the wires are visible, it is necessary to shift the position of the tube 2. However, when such movement takes place and the conductors are hidden from view, the conductors are liable to lie directly in engagement with each other with the resultant danger of ultimate short-circuiting them.

I permit relative movement between the conductor and insure that the insulating device is always in position by providing the cross conductors of the branch circuit 16 and the conductor 15 with my insulating devices 2. The time required for applying the insulating device 2 is much less than that which has heretofore been required in taping a tube on the conductor. It is to be understood that various changes may be made in the invention without departing from the scope of the following claims.

I claim:

1. In an insulating device, a base having a groove therein, outwardly extending portions disposed on opposite sides of the groove, the outwardly extending portions having aligned openings therein, and a member having an opening therethrough disposed between said portions and above the groove whereby an electrical conductor extending through the openings in the projecting portions and the second member secures the latter in place.
2. An insulating device comprising a base member of U-shape, the arms of which are provided near their ends with aligned openings, a groove at the bottom of the base for the reception of an electrical conductor, and a roller of insulating material mountable between the arms of the yoke and having an opening for alignment with the openings in the arms of the yoke whereby an electrical conductor extending through the several openings secures the roller in place and the roller secures an electrical conductor in said groove.
3. In an insulating device, a base having a seat for an electrical conductor, an electrical distribution conductor or wire seated therein, closure means of insulating material extending across the seat, and means for holding the closure means in place comprising a second distribution conductor or wire extending through the base, through the closure means, and then through the base whereby the closure means serves as an insulating medium between the conductors.

In testimony whereof I have hereunto set my hand.

WILLIAM BROAD.
